CATHODE FOR ELECTRIC DISCHARGE DEVICES

Edgar Römhild, Berlin-Steglitz, Germany, assignor to General Electric Company, a corporation of New York

Application January 15, 1932, Serial No. 586,933
In Germany January 22, 1931

6 Claims. (Cl. 250—27.5)

The present invention relates to cathodes for electric discharge devices and more particularly to cathodes designed to carry large current at relatively low voltage.

5 Heavy current cathodes of large power tubes are sometimes constituted of metal strips having a serpentine, loop or spiral configuration and presented edgewise to the anode. These shapes are desirable in order to obtain large cathode surfaces in relatively small spaces and to minimize 10 radiation of heat. When cathodes of this sort are heated, the folds or convolutions, upon expansion, tend to distort and to change their relative position with respect to one another and also 15 with respect to the cooperating electrode, thus causing deleterious operating effects. Furthermore, these cathodes are subject to mechanical distortion by rough handling.

An object of the present invention is to provide 20 an improved arrangement for holding a cathode structure of the type referred to rigidly in shape under unheated conditions, i. e., during manufacture; also under heated conditions as when being operated. This object is attained in brief, 25 by forming the strip into a series of recurring reverse loops of which the inner portions are held rigidly between two grooved insulating disks. The latter may be supported on a central rod to which they are rigidly secured.

30 The invention will be better understood when reference is made to the following description and accompanying drawing in which Fig. 1 is a cross-sectional view of a cathode bent to form and shown as being fitted into one of the insulating disks or plates; Fig. 2 is a cross section 35 taken along line 2—2 in Fig. 1; Fig. 3 shows the disposition of the improved cathode with respect to an anode of an electron discharge device; Fig. 4 is a diagrammatic view of an improved 40 cathode provided with a control member and a cooperating anode; Fig. 5 shows plan and elevational views of the insulating plate.

Referring to Fig. 1, numeral 1 designates a strip 45 form of cathode constituted of a member of bent and straight portions which take the general design of a clover leaf. The cathode may be fabricated of any suitable metal, for example, nickel, and if desired, coated with electronically active material. As shown more clearly in Figs. 2 and 5, 50 the inner portions of the cathode are held rigidly between two circular plate members or disks 2 constituted of insulating material. These members are held at the proper distance apart by a spacer member 3 of insulating material and the 55 entire assemblage arranged on a metal rod 4 to

which it is rigidly secured by a washer 5 and pins 6 driven through the rod. The plates 2 are provided with channels or grooves 7 which receive snugly the inner loops.

As shown in Fig. 1, one of the inwardly projecting loops of the cathode may be broken to provide terminals 8 for the application of alternating or direct current. If desired, the loops may be entirely unbroken so as to form a continuous annulus and provided with connections at 10 symmetrally disposed points on the cathode to which a multi-phase voltage may be applied. It is evident that regardless of the manner in which current is passed through the cathode, the structural arrangement, including the supporting disks 15 2, the spacer 3 and the central rod 4, is such as to preclude any movement of the cathode as a whole, or the individual portions thereof in any direction. As the cathode is heated, the resulting expansion is taken up by the lengthening of the individual convolutions, which simply results in a slightly increased outer diameter of the cathode and does not produce distortion of the individual loops because the metal is free to move longitudinally through the grooves. It is also apparent 20 that a cathode of the type shown, when presented edgewise to an anode is capable of producing a large electron current by reason of its active surface and configuration which tends to prevent undue heat radiation; also on account of the 25 large extent of the surface. A cathode of this type is relatively easy to manufacture and assemble.

In Fig. 3, I have indicated the spacial relation 30 of the improved cathode with respect to an anode 35 of an electron discharge device. Numeral 9 designates an anode of symmetrical shape such as a frustum of a cone, and presented endwise to the cathode. In order to prevent the anode from being coated with active material sputtered from 40 the cathode, the latter may be provided with a metal shield 10 in the form of a shallow dish with the concave surface presented to the cathode. The shield member may be provided with a raised portion 11 secured to the central rod 4 in any 45 suitable manner, for example, by a pin 12 driven through the rod.

The improved form of cathode lends itself to 50 electron discharge devices of the electrostatically controlled type. Thus, in Fig. 4, I show a metal 55 cylinder 13 surrounding a loop cathode of the improved type and closed at both ends except for perforated portions for the escape of electrons. The cylindrical member terminates in a metal tube 14 which may be sealed to the glass envelope. 55

lope of an electron discharge device. The central rod member 4 may also be secured to a stem. The upper end portion of the electrostatic control member is provided with a flange extension 5 15 which carries a pin 16 driven through the central rod. The structure as a whole, i. e., the improved cathode and grid member, is thus arranged in a compact and rigid unit which precludes relative movement between the cathode 10 and grid so that small spaces may be accurately maintained between the electrodes. A combined cathode and grid structure of this sort may be employed in connection with a symmetrical form of anode 9 to which it is presented endwise.

15 What I claim as new and desire to secure by Letters Patent of the United States, is:

1. A cathode for an electron discharge device comprising a metallic strip member bent into recurrent inner and outer loops and arranged about 20 a central support member, means for securing the inner loops to the support member, said means comprising a pair of insulating plates containing grooves which receive the loops.
2. A cathode for an electron discharge device comprising a metallic strip bent into recurrent inner and outer loops and arranged about a central support member, means for securing the inner loops to the support member, said means comprising a pair of insulating plates spaced apart 25 by an insulating member, said plates serving to clamp the strip between them.

3. A cathode for an electron discharge device comprising a metallic strip having recurrent loops which form in the aggregate, roughly a cylinder, a support member mounted in the axis of the cylinder, and extending over and secured to the edges of said loops. 5

4. A cathode for an electron discharge device comprising a metallic strip having recurrent loops which form in the aggregate, roughly a cylinder, a support member mounted in the axis of the cylinder and secured at both ends to said loops. 10

5. A cathode for an electron discharge device comprising a metallic strip bent into recurrent loops and forming a complete annulus, said annulus being provided with terminals, greater in 15 number than two, equidistantly spaced about the periphery of the annulus for the application of multi-phase alternating current to the cathode.

6. An electron discharge device including a cathode, an electrostatic control member and an 20 anode, said cathode and electrostatic control member secured together as a unit, said cathode being constituted of strip material presented edgewise to said anode and having recurrent loops arranged about and supported from a central 25 member, said control member being constituted of a perforated cylinder secured to said central support member.

EDGAR RÖMHILD.
